(57) **CLAIM**

The ornamental design for a label with surface ornamentation, as shown and described.

DESCRIPTION

The patent or application file contains at least one drawing executed in color. Copies of this patent or patent application publication with color drawing(s) will be provided by the Patent and Trademark Office upon request and payment of the necessary fee.

FIG. 1 is a front view of our new design of a label with surface ornamentation, shown in gray scale;

FIG. 2 is a front view of an alternate embodiment of the design shown in color;

FIG. 3 is a perspective view of a package ornamented with an alternate embodiment of the design, shown in gray scale;

FIG. 4 is a front view of the package and the design thereof;

FIG. 5 is a back view of the package thereof;

FIG. 6 is a side view of the package thereof;

FIG. 7 is a view of the opposite side of the package thereof; and,

FIGS. 8 and 9 are top plan and bottom views of the package thereof;

FIG. 10 is a perspective view of a package ornamented with an alternate embodiment of the design, shown in gray scale; FIG. 11 is a front view of the package and the design thereof; FIG. 12 is a back view of the package thereof;

FIG. 13 is a side view of the package thereof;

FIG. 14 is a view of the opposite side of the package thereof; and,

FIGS. 15 and 16 are top plan and bottom views of the package thereof.

The broken lines shown in the drawings depict environmental subject matter only and form no part of the claimed design.
